CLAIM

The ornamental design for a cover for a jack handle assembly, as shown and described.

DESCRIPTION

FIG. 1 is a perspective view of my invention for a cover for a jack handle assembly;

FIG. 2 is a top view of the invention;

FIG. 3 is a bottom view of the invention;

FIG. 4 is a right side view of the invention;

FIG. 5 is a left side view of the invention;

FIG. 6 is a front view of the invention; and,

FIG. 7 is a rear view of the invention.

The broken lines in the figures depict environment and form no part of the claimed design.
